OIL WELL PUMPING APPARATUS

Harry F. Vickers, Kenneth R. Herman and Jesse Moser, Detroit, Mich., assignors to Vickers Incorporated, Detroit, Mich., a corporation of Michigan

Original application January 15, 1940, Serial No. 313,862. Divided and this application October 25, 1940, Serial No. 362,818

8 Claims. (Cl. 103—38)

1

This invention relates to a stroke control for variable displacement pumps.

It is an object of the present invention to provide a stroke control which will greatly reduce the shock due to change of direction of flow through the pump as well as to control the acceleration and deceleration movements where the pump is used in a system in which the speed of an operating member is directly controlled by the pump displacement.

A further object of the invention is to provide a stroke control piston which permits extremely rapid operation, that is, extremely rapid reversals of flow through a variable volume pump.

This is a divisional application of a co-pending application, Serial No. 313,862, filed January 15, 1940.

Other objects and features of the invention, including the shape of the control piston and the arrangement of restriction valves will be brought out in the following description and claims.

In the drawing:

Fig. 1 is a sectional view illustrating a variable displacement pump diagrammatically and showing in detail the stroke control device.

Figs. 2 and 3 illustrate a portion of Fig. 1 showing the stroke control valve in a different relative position.

Referring to the drawing, in Fig. 1 a control rod 143 is connected to a lever 144 which in turn is fastened to a rod 145, the function of which will be later described. The pump to be controlled is shown at 160 and is driven by an electric motor 161. This pump is a reversible variable delivery pump having a shiftable control member 166 to control the direction of flow of liquid through the pump and the displacement of the pump.

This type of pump is well known and will not be explained in detail except to say that when the movable head 166 is on one side of the center line, the flow through the pump will be in one direction, and when it is on the other side of the center line the flow through the pump will be in the other direction. The volume flow is always proportional to the displacement of the member 166 from the center line, that is, the greater the angle of the member 166 with the center line, the greater the volume output of the pump. It will be seen from this that as the member 166 crosses the center line the direction of flow through the pump will change.

The direction of liquid flow through the pump and the volume of displacement is indirectly controlled by the group of elements which consist

2

of a stroke control piston 167, a pilot pressure control valve 168 and a pilot pressure pump 169. A relief valve 170 is provided to limit the output pressure of pump 169. The valve 168 is connected by a rod 146 and a lever 147 to shaft 145 previously described. The valve 168 is shiftable in a bore in a housing 180 to perform certain functions hereinafter described in detail. Leading from pump 169 is a conduit 177 which connects to an annular port 181 in the valve housing 180. This port surrounds the bore of valve 168. When valve 168 is in the position shown in Fig. 1, pilot pressure from the pump 169 may pass the valve to a second annular port 182 which 10 leads to a conduit 183. The corresponding conduit 184 leads from the port 185 which will be connected to port 181 if valve 168 is shifted to the left from the position shown in Fig. 1. When conduit 183 is connected to pressure it will be 20 seen that conduit 184 is connected to the tank through a conduit 186 and similarly, if conduit 184 is connected to pressure, conduit 183 will be connected to the tank through the conduit 186.

The top part of the housing 180 is provided 25 with a recess in which reciprocates the stroke control piston 167. This recess consists of two spaced chambers 188 and 189 connected by a slightly restricted passage 190. Adjacent each end of the restricted passage are annular ports 30 191 and 192. The stroke control piston consists of a rod 193, one end of which is connected to the member 166, and two piston spools 194 and 195. Each of these spools is tapered from a center portion which has a diameter arranged to 35 have a sliding fit with the restricted portion 190 of the housing. The central portions of the spools are wide enough to cover the annular ports 191 and 192 if positioned directly over them. Conduits 183 and 184 each split three ways. The 40 ports 191 and 192 are connected, respectively, to conduits 183 and 184 through restrictions 196 and check valves 197 which permit flow from the ports to the conduit. The outer ends of the two chambers 188 and 189 are connected to conduits 183 and 184, respectively, by conduits 198 in which are check valves 199 which permit flow from the conduits to the chambers. A third branch from conduits 183 and 184 consists of a 45 restricted opening 200 which opens to the chambers 188 and 189 at about the central portion.

The restrictions 196 and 200 in housing 180 consist of small discs spaced in a cylindrical recess and provided with a small central aperture. 50 The operation of the control lever 143 may be either manual or it may be connected up to some

The restrictions 196 and 200 in housing 180 consist of small discs spaced in a cylindrical recess and provided with a small central aperture. The operation of the control lever 143 may be either manual or it may be connected up to some

operating element of a mechanism so that reversal is effected automatically.

The stroke control piston 167 is particularly adapted for high speed operation. As the parts are viewed in Fig. 1, it will be seen that pilot pressure has just completed the movement of piston 167 to the left. As a result of this movement the volume control member 166 of the pump 160 has been shifted to its extreme left position as shown. When the lever 143 is again shifted to effect a leftward movement of valve 168, pilot pressure may then be admitted from conduit 171 to conduit 184 while conduit 183 will be connected to the tank. In the movement of piston 167 to the right, pressure will pass to the left end of the piston through the restriction 200 and the check valve 199. The liquid on the right hand side of the piston 167 has, at the start of the movement, two outlets, one through check valve 197 and restriction 196 and the other through restriction 200. As the piston 167 reaches the mid-point of its movement so that part 166 is just passing dead-center, the port 191 will be closed by the spool 195. At this time, it will be seen that the only outlet of liquid from the right hand side of the piston 167 is the restriction 200. Consequently, there will be a gradual reduction in speed of the piston 167 as the tapered portion on spool 195 gradually closes off port 191. Piston 167 is illustrated in its mid-position in Fig. 3. As piston 167 continues to the right, port 191 will again be gradually opened, and there will again be two outlets for the liquid to the right of the piston, namely, check valve 197 and the restriction 200. Piston 167 is shown in a second position in Fig. 2. The design of the stroke control piston 167 and the various outlets for the cylinder in which it is located, thus achieves a movement in which there is a gradual reduction of speed just prior to the mid-point of the movement and a gradual increase in speed beyond this point. The slow movement of the piston takes place at just the point where the pump 60 is reversing flow and because of the arrangement as described, there will be a very smooth operation. Other than at the mid-point of the movement, the piston 167 may be operated rapidly and thus permit rapid operation of the system. At the end of the stroke of the piston in either direction, it will be seen that port 191 or 192 will be gradually closed so that there will be a deceleration of movement at this part of the stroke.

We claim:

1. In a hydraulic circuit, of the type having a variable displacement pump, and a shiftable member on said pump arranged to control direction of flow through said pump, a control system for said member comprising a source of pilot pressure, means for directing said pilot pressure, a control cylinder for receiving said pilot pressure, a piston in said control cylinder adapted to be operatively connected to said shiftable member, and means for controlling the volume of liquid delivered to said last named piston whereby the movement of said piston in said control cylinder is gradually decreased and then increased during the central portion of a stroke of said piston in changing the direction of the flow through said pump.

2. In a hydraulic circuit, of the type having a variable displacement pump, and a shiftable member on said pump arranged to control direction of flow through said pump, a control system for said member comprising a source of pilot pressure, means for directing said pilot pressure, a

control cylinder for receiving said pilot pressure, a piston in said control cylinder adapted to be operatively connected to said shiftable member, said control cylinder having a plurality of restricted openings at each end adapted to serve as control outlets for liquid confined within said cylinder and a port formed in said cylinder connected to one of said outlets and adapted to be temporarily closed during an intermediate portion of a stroke of the piston in said cylinder to effect gradual deceleration and acceleration at a predetermined intermediate point in the piston stroke during the change of direction of fluid flow in the variable displacement pump.

15. 3. In a hydraulic circuit, of the type having a variable displacement pump, and a shiftable member on said pump arranged to control direction of flow through said pump, a control system for said member comprising a source of pilot pressure, means for directing said pilot pressure, a control cylinder for receiving said pilot pressure, a piston in said control cylinder adapted to be operatively connected to said shiftable member, said control cylinder having a plurality of restricted openings at each end adapted to serve as control outlets for liquid confined within said cylinder and a port formed in said cylinder connected to one of said outlets and adapted to be temporarily closed during portions of a stroke of the piston in said cylinder to effect gradual deceleration and acceleration at an intermediate point in the piston stroke and gradual deceleration at the end of a stroke.

4. In a hydraulic system, of the type having a reversible variable displacement pump, and movable means on said pump to control the direction and displacement thereof, a control means for said movable means comprising a cylinder and a piston reciprocal therein, a rod on said piston adapted to be connected to said movable means, said cylinder comprising a housing having two spaced end chambers connected by a passage slidably receiving said piston, unrestricted inlets to each of said chambers, restricted outlets from ports spaced in said passage, said piston comprising spaced portions to be slidably received by said passage and portions to each side of said spaced portions tapered to said spaced portions, said spaced portions being adapted to close said ports in passing them and being so arranged that one of said ports leading to an outlet will be closed during intermediate and final stages of movement of the piston to cause, during each closing, a gradual deceleration of the movement of the piston.

5. In a hydraulic system, of the type having a reversible variable displacement pump, and movable means on said pump to control the direction and displacement thereof, a control means for said movable means comprising a cylinder and a piston reciprocal therein, a rod on said piston adapted to be connected to said movable means, said control cylinder having a plurality of restricted openings at each end adapted to serve as control outlets for liquid confined within said cylinder and a port formed in said cylinder connected to one of said outlets and adapted to be temporarily closed by said piston during portions of a stroke of the piston in said cylinder to effect gradual deceleration and acceleration at an intermediate point in the piston stroke and gradual deceleration at the end of a stroke.

6. In a hydraulic system, a source of pressure a means to be operated by pressure from said source including a cylinder comprising a housing having two spaced end chambers enlarged from

a connecting passage, conduits leading to each end of said cylinder, each conduit branching to the cylinder in a unidirectional unrestricted inlet, a restricted outlet leading to a port in said passage and a two-way restricted inlet-outlet, a piston in said cylinder adapted to slide in the passage therein and arranged at either end of its stroke and at an intermediate point to close one or more of said restricted outlets, said piston comprising spaced portions to be slidably received by said passage, said spaced portions being adapted to close said ports in passing them and being so arranged that one of said ports, leading to an outlet, will be closed during intermediate and final stages of movement of said piston to cause, during each closing, a gradual deceleration of the movement of the piston.

7. In a hydraulic system, a source of pressure, a means to be operated by pressure from said source including a cylinder comprising a housing having two spaced end chambers enlarged from a connecting passage, conduits leading to each end of said cylinder, each conduit branching to the cylinder in a unidirectional unrestricted inlet, a restricted outlet leading to a port in said passage and a two-way restricted inlet-outlet, a piston in said cylinder adapted to slide in the passage therein and arranged at either end of its stroke and at an intermediate point to close one or more of said restricted outlets, said piston comprising spaced portions to be slidably received by said passage, and portions to each side of said spaced portions tapered to said spaced portions, said spaced portions being adapted to close said ports in passing them and being so arranged that one of said ports, leading to an outlet, will be

5 closed during intermediate and final stages of movement of said piston to cause, during each closing, a gradual deceleration of the movement of the piston.

10 8. In a hydraulic system, a source of pressure, a means to be operated by pressure from said source including a cylinder comprising a housing having two spaced end chambers connected by a passage, conduits leading to each end of said cylinder, each conduit branching to the cylinder in a unidirectional unrestricted inlet, a restricted outlet leading to a port in said passage and a two-way restricted inlet-outlet, a piston in said cylinder adapted to slide in the passage therein and arranged at either end of its stroke and at an intermediate point to close one or more of said restricted outlets, said piston comprising spaced portions to be slidably received by said passage, said spaced portions being adapted to close said ports in passing them and being so arranged that one of said ports, leading to an outlet, will be closed during intermediate and final stages of movement of said piston to cause, during each closing, a gradual deceleration of the movement of the piston, valve means to alternately connect one of said conduit means to pressure and the other to tank, and valve means in said restricted outlets subject to pressure in said conduit means whereby when one of said conduit means is connected to pressure its respective restricted outlet will be closed and the other two branches thereof will serve as inlets to said cylinder.
